United States Patent Office

Des. 228,157

Patented Aug. 14, 1973

228,157

COMPACT

Morris Sussman, Freeport, N.Y., assignor to Shore Plastics Inc., Freeport, N.Y.

Filed Nov. 22, 1971, Ser. No. 201,267

Term of patent 14 years

Int. Cl. D3—02

U.S. Cl. D86—10 N

FIG. 1 is a top plan view of the cover of a compact showing my new design;

FIG. 2 is a top plan view of the container of a compact showing my new design;

FIG. 3 is a top plan view of the assembled compact;

FIG. 4 is a top plan view with the cover rotated to an alternate position;

FIG. 5 is a bottom plan view; and

FIG. 6 is a side elevational view.

I claim:

The ornamental design for a compact, as shown and described.
